UNITED STATES PATENT OFFICE.

JOSEPH WOLFF, OF BROOKLYN, NEW YORK, ASSIGNOR TO SONORA PHONOGRAPH CORPORATION, A CORPORATION OF NEW YORK.

DESIGN FOR A CARRYING-CASE FOR PHONOGRAHS OR SIMILAR ARTICLES.

53,953.

Specification for Design.

Patented Oct. 7, 1919.

Application filed March 10, 1917. Serial No. 154,042. Term of patent 14 years.

To all whom it may concern:

Be it known that I, JOSEPH WOLFF, a subject of His Majesty the King of Great Britain, residing in the borough of Brooklyn, county of Kings, city and State of New York, have invented a new, original, and ornamental Design for a Carrying-Case for Phonographs or Similar Articles, of which the following is a specification, reference being had to the accompanying drawings, forming a part thereof.

In the drawings,—

Figure 1 is a perspective view of a phonograph carrying case, in open position, illustrating my improved design.

Fig. 2 is a central, vertical cross-sectional view of the top or cover of the case.

I claim:

The ornamental design for a carrying case for phonographs or similar articles, substantially as shown.

This specification signed and witnessed this 26th day of February, 1917.

JOSEPH WOLFF.
